Frederick Wright

UNITED STATES PATENT OFFICE.

WILLIAM MORLEY MARTIN, OF REDRUTH, ENGLAND.

APPARATUS FOR THE WATER CONCENTRATION OF ORES OR THE LIKE.

1,207,967.

Specification of Letters Patent. Patented Dec. 12, 1916.

Application filed January 24, 1916. Serial No. 73,972.

To all whom it may concern:

Be it known that I, WILLIAM MORLEY MARTIN, a subject of the King of Great Britain, residing at Meadowcroft, West 5 Trewirgie, Redruth, Cornwall, England, have invented new and useful Improvements in Apparatus for the Water Concentration of Ores or the like, of which the following is a specification.

- 10 Apparatus for the water concentration of ores or the like consists according to this invention of a revolving drum whose inner circumference is adapted to lift the values but not the gangue from a mixture of ore and water at the bottom of the drum. This is effected by forming the inner surface of the drum of frosted fluted glass which provides markings consisting of flutes and pits which serve to lift the values without lifting the 15 gangue. The depth of the flutes should be from a sixteenth to one thirty-second of an inch with from 16 to 40 flutes per inch according to the mesh of the pulp and the assay value of same. When the ore to be 20 treated contains values of different sizes the markings may consist of a plurality of microscopic pits of different sizes, one series of pits being of a size best adapted to lift the values of one size and the other series of pits 25 of a size best adapted to lift the values of the other size and so on. It is desirable first to ascertain approximately by microscopic examination the sizes of the mineral particles in the pulp to be concentrated and use a 30 microscopic frost near to but of course larger than the varying sizes. This is effected by subjecting glass to a sand blast first with a sand of one size say 40 mesh sand and then with a sand of another size say 60 mesh sand, 35 the other conditions being the same. By this means several different sized frostings can be obtained on the same glass surface.

The invention is illustrated in the accompanying drawings.

- 40 Figure 1 is a sectional elevation and Fig. 2 is a section on the line 2—2 of Fig. 1.

In the drawings *a* is a drum turning on ball bearings in a ring *b* and driven in any suitable manner for example as indicated by 45 teeth *b'*. The inner circumference of the

drum is lined with glass *c* having on one surface flutes parallel with the axis of the drum, the fluted glass being frosted as before described. The sides of the drum are flanged at *d* and *d'* the flange *d'* being of a 55 size to retain a small quantity only of pulp in the drum say two to four inches.

e is an inclined glass plane carried by brackets *f* which also carry a pipe *g* fitted with spraying nozzles; *e* extends from side 60 to side of the drum *a* and forms joint with it by the aid of rubber flaps *h*.

i is a launder leading ore and water into the drum.

j is a launder leading away the values and 65 *k* is a launder leading away gangue and water from the drum *a* when the level rises above the flange *d'*.

The apparatus works as follows:—A mixture of metalliferous sand for example and 70 water is fed from the launder *i* to the slowly revolving drum *a*. The frosted flutes on the glass surface *c* coming into contact with the values raise them and they are at the upper portion of the drum acted upon by the 75 sprays and so become detached. The values fall onto the inclined plane *e* and pass into the launder *j*. The gangue and water when above the flange *d'* flow away by the 80 launder *k*.

In my application for Patent No. 35,645, filed June 22, 1915, I have shown and described an apparatus for concentrating ores in which the acting surface consists of frosted material, such as glass, having a plural- 85 ity of pits of different sizes adapted to cause great hindrance to the movements of the values and such application also shows and describes an acting surface consisting of fluted, frosted material, such as glass, and 90 furthermore such application shows and describes a concentrating apparatus comprising a rotary concentrating table, the acting surface of which consists of frosted and fluted glass and claims to such subject matter are made in the above mentioned application.

What I claim is:—

1. An apparatus for concentrating ores comprising a drum revolving about a hori- 100

zontal axis and whose inner surface is formed of glass having flutes parallel with the axis of the drum provided with a plurality of microscopic pits.

- 5 2. An apparatus for concentrating ores, comprising a drum revolving about a hori-

zontal axis and whose inner surface is formed of glass having flutes parallel with the axis of the drum provided with a plurality of microscopic pits of varying sizes.

WILLIAM MORLEY MARTIN.
